[57] CLAIM

The ornamental design for a control panel for a combined vehicular radio receiver, cassette player and digital clock, as shown and described.

DESCRIPTION

FIG. 1 is a top plan view of a control panel for a combined vehicular radio receiver, cassette player and digital clock showing our new design;

FIG. 2 is a front elevational view thereof;

FIG. 3 is a bottom plan view thereof;

FIG. 4 is a left side elevational view thereof; and,

FIG. 5 is a right side elevational view thereof.

The broken line showing is for illustrative purposes only and forms no part of the claimed design.

FIG. 1

FIG. 2

FIG. 3

FIG. 4

FIG. 5

UNITED STATES PATENT AND TRADEMARK OFFICE
CERTIFICATE OF CORRECTION

PATENT NO. : D334,753
DATED : April 13, 1993
INVENTOR(S) : Dziekan, et al

It is certified that error appears in the above-identified patent and that said Letters Patent is hereby corrected as shown below:

ON THE TITLE PAGE, in Assignee item #73, insert --Chrysler Corporation--

Signed and Sealed this
Fifth Day of July, 1994
